CHECK ROLL HOLDER

Evangel A. Haveles, Los Angeles, Calif.

Application January 18, 1939, Serial No. 251,564

7 Claims. (Cl. 164—111)

My invention relates to a holder for continuous rolls of checks such as restaurant checks in combination with means for punching checks to indicate the amount of the check and the objects of 5 my invention are:

First, to provide a novel means of supporting and holding a roll of checks so that they may be unrolled and used in sections;

Second, to provide a holder of this class with 10 novel punching means for the opposite sides of the checks;

Third, to provide a holder of this class in which the punches may be operated in unison or separately as desired;

15 Fourth, to provide a holder of this class in which the punches are operated upwardly through the checks so that the checking operation can be seen clearly from above;

Fifth, to provide a holder of this class in which 20 a roll may be placed in a casing and is supported loosely therein and is unwound as used;

Sixth, to provide a holder of this class with a 25 napkin holder in combinative relation with the lid of the check roll casing;

Seventh, to provide a holder of this class in which the punching apparatus is positioned and supported on the lid or cover of the roll casing and napkin casing;

Eighth, to provide a holder of this class with a 30 menu holder in connection therewith;

Ninth, to provide a holder of this class with 35 novel means for securing it to a desk counter or the like;

Tenth, to provide a holder of this class with 40 means for supporting a glass and salt and pepper receptacles in connection therewith;

Eleventh, to provide a holder of this class which is very simple and economical of construction, efficient in its action and which will not 45 readily deteriorate or get out of order.

With these and other objects in view as will appear hereinafter, my invention consists of certain novel features of construction, combination and arrangement of parts and portions as 50 will be hereinafter described in detail and be particularly set forth in the appended claims, reference being had to the accompanying drawing and to the characters of reference thereon which form a part of this application in which:

Figure 1 is a front side elevational view of my 55 check roll holder showing portions broken away to facilitate the illustration and showing the holder secured in position on a table or counter shown fragmentarily with section lines; Fig. 2 is a top or plan view of the same; Fig. 3 a transverse sectional view taken through 3—3 of Fig. 1; Fig. 4 is a sectional view on an enlarged scale taken from the line 4—4 of Fig. 1; and Fig. 5 is a transverse sectional view taken from the line 5—5 of Fig. 4.

Similar characters of reference refer to similar parts and portions throughout the several views of the drawing:

The check roll casing 1, napkin casing 2, supports 3, lid 4, punch levers 5 and 6, punch members 7 and 8, punch member springs 9 and 10, punch die plate 11, and glass, salt and pepper holders 12 constitute the principal parts and portions of my check roll holder.

The check roll casing 1 is a box like casing 10 preferably made of sheet metal of a size adapted to receive a roll of checks substantially four inches in diameter and two to two and one-half inches wide. It is provided with a bottom member 1a which extends and forms the bottom for a napkin casing 2. It is extended at one side and extends downwardly at 1b for some distance and is provided with an offset integral portion 1c, thus providing a receiver for menu cards, or the like.

Secured across the opposite ends of the bottom member 1a and extending downwardly and then 15 backwardly are the supports 3, the backwardly extending portions 3a being threaded and in which is mounted a bolt 3b, the end of said bolt being adapted to be screwed up against the lower side of the table or counter as shown best in Figs. 1 and 3 of the drawing, thus providing means for 20 supporting the casing. The casing 2 is also box shape and is preferably composed of metal and is 25 of the size to receive folded napkins, it being noted that it is provided with an opening 2a at its front upper side shown best in Fig. 1 of the drawing, through which one of the napkins is 30 adapted to be drawn for use. This casing 2 is 35 provided with a napkin supporting plate 2b which rests against the back side of the inner wall of the casing and is provided with two spaced springs 2c which are adapted to rest against the napkins and hold them up in position against 40 the front wall, so that they may be easily extracted through the opening 2a. It will be noted that the side wall of the napkin casing and the check roll casing are separated by a common 45 partition 2d shown best in Fig. 1 of the drawing. Positioned below the bottom member 1a and extending from the front side thereof is a plate 50 which forms a holder for a glass, salt and pepper shaker or the like and rests upon the table and is secured by clamping of the holder in position against the upper face of the table or counter. This partition 2d is spaced at its upper side some 55 distance from the upper side of the casings 1 and 2, as shown best in Fig. 4 of the drawing. Pivotally mounted at the one end of the casing member 1 and extending over the top open sides of both the casings 1 and 2 is the lid 4 which is provided with a downwardly extending flange portion 4a on both sides and on the free end overlapping the upper edge of the casings 1 and 2 as 60

shown. It will be noted that the lid is hinged in slightly spaced relation from the side wall of the casing 1 so that the paper checks extend outwardly through an opening 1d and then extends under a strip 4b of the lid 4, there being provided slots on each side of this strip 4b to permit the paper to pass down under this strip 4b. This lid member 4 is also provided with an opening 4c in which is mounted a plate 11 which is provided with downwardly extending ends 11a at its opposite ends. Secured to this member 4 is an L member 4d which supports a plate 4e and secured to this plate 4e is a member 4f which is L shaped, the upper horizontal portion of which extends substantially parallel with the member 4 and in spaced relation with the horizontal portion of the member 11. The lower end of this member 4e is provided with a roller portion 4g which forms a journal or bearing for the inner ends of the lever members 5 and 6 shown best in Fig. 4 of the drawing. Shiftably supported in the member 4f and in lugs 4h from the member 4f are the punch members 7 and 8 which are held downwardly by means of springs 9 and 10. These members 7 and 8 are provided with heads which are adapted to engage with curved portions 5a and 6a on the levers 5 and 6 so that when these levers 5 and 6 are depressed, these punch members 7 or 8 are moved upwardly to punch holes in the checks. The member 11 is provided with holes adapted to receive the ends of the punch members 7 and 8 with the check interposed between the members 4f and 11 when the levers 7 or 8 are operated and the checks are punched, it being noted that these punches are in alignment with the price check on the sections of the check roll which is provided with perforated lines separating the several checks.

The operation of my check roll holder is substantially as follows: The check roll R as shown in Fig. 1 of the drawing is placed in the check holder 1 and the end of the continuous check roll is threaded out through the opening 1d, then under the strip 4b and the end between the members 4f and 11 so that the holes for the punch member in the member 11 are in alignment with the checks for punching the squares in alignment with the price on opposite sides of the check as shown best in Fig. 2 of the drawing. The check is drawn under the members 11 and 4b to the proper position and either one of the levers 5 or 6 are punched in accordance with the charge of the check. The checks simply roll off of the roll and the roll rolls around in the casing 1 as the checks are gradually rolled off. The spring member 9 tends to depress the punch member as soon as the hole is punched through the check.

Though I have shown and described a particular construction, combination and arrangement of parts and portions, I do not wish to be limited to this particular construction, combination and arrangement but desire to include in the scope of my invention the construction, combination and arrangement substantially as set forth in the appended claims.

Having thus described my invention, what I claim as new and desire to secure by Letters Patent is:

70 1. In a check roll holder of the class described, a hollow casing member adapted to receive a roll of checks, a lid pivotally supported thereon

near one side leaving an opening through which the end of the checks is threaded, a keeper member on said lid through which said checks are threaded, and a punch plate positioned slightly above said lid in spaced relation from said keeper member.

2. In a check roll holder of the class described, a hollow casing member adapted to receive a roll of checks, a lid pivotally supported thereon near one side leaving an opening through which the end of the checks is threaded, a keeper member on said lid through which said checks are threaded, a punch plate positioned slightly above said lid in spaced relation from said keeper member, and a pair of punch members operative upwardly through said punch plate for perforating said checks.

3. In a check roll holder of the class described, a hollow casing member adapted to receive a roll of checks, a lid pivotally supported thereon near one side leaving an opening through which the end of the checks is threaded, a keeper member on said lid through which said checks are threaded, a punch plate positioned slightly above said lid in spaced relation from said keeper member, a pair of punch members operative upwardly through said punch plate for perforating said checks, and separate lever means on opposite sides of said lid for engagement with said punch members for operating the same independently.

4. In a check holder of the class described, a roll casing provided with a pivotally supported lid, means on said lid for supporting the end of the checks from said roll, punch members mounted on said lid below the same and adapted to extend up through said lid for punching the checks on said lid.

5. In a check holder of the class described, a roll casing provided with a pivotally supported lid, means on said lid for supporting the end of the checks from said roll, punch members mounted on said lid below the same and adapted to extend up through said lid for punching the checks on said lid, and lever means extending at opposite sides of said lid adapted to be depressed for operating said punch members.

6. In a check holder of the class described, a roll casing provided with a pivotally supported lid, means on said lid for supporting the end of the checks from said roll, punch members mounted on said lid below the same and adapted to extend up through said lid for punching the checks on said lid, lever means extending at opposite sides of said lid adapted to be depressed for operating said punch members, and spring means tending to force said punch means downwardly when released.

7. In a check holder of the class described, a roll casing provided with a pivotally supported lid, means on said lid for supporting the end of the checks from said roll, punch members mounted on said lid below the same and adapted to extend up through said lid for punching the checks on said lid, lever means extending at opposite sides of said lid adapted to be depressed for operating said punch members, spring means tending to force said punch means downwardly when released, and said lid provided with an extended portion adapted as a base for writing on said checks.
